A. D. Jackson,

ATTORNEY.

UNITED STATES PATENT OFFICE.

GEORGE W. DEATS, OF FORT WORTH, TEXAS.

APPARATUS FOR CLEANING DEEP WELLS.

1,235,770.

Specification of Letters Patent.

Patented Aug. 7, 1917.

Application filed May 29, 1916, Serial No. 100,556. Renewed July 3, 1917. Serial No. 178,484.

To all whom it may concern:

Be it known that I, GEORGE W. DEATS, a citizen of the United States, residing at Fort Worth, in the county of Tarrant and State of Texas, have invented certain new and useful Improvements in Apparatus for Cleaning Deep Wells, of which the following is a specification.

My invention relates to cleaning apparatus for deep wells and more particularly to apparatus for breaking up and cleaning matter which has become caked or set at the lower end of deep well pumping apparatus, such as mud, paraffin, and other substances. 10 In oil wells, paraffin becomes caked about the bottom of the pumping apparatus and renders the oil wells useless. One of the objects of this invention is to provide an apparatus for breaking up the caked paraffin and other material or substances and removing the same from the well and also to break up and clean out the paraffin which forms in the pipes and between the walls of the pipes. Advantage is taken of the property 15 of paraffin which makes it easily melted. Hot steam is used to melt or break up the caked paraffin so that it can be forced out of the well. Steam and compressed air are also used by the same apparatus for breaking 20 and removing mud and sand and gravel which has become settled about the bottom of the pipes and also to blow the strata between different wells. Other objects and advantages will be fully explained in the following description and the invention will be 25 more particularly pointed out in the claims.

Reference is had to the accompanying drawings which form a part of this application.

40 Figure 1 is a broken diagrammatic view, showing a side elevation of a cleaning and pumping apparatus and broken sections of two line pipes of adjacent wells. Fig. 2 is a broken vertical section of the well cleaning apparatus shown in Fig. 1. Fig. 3 is a similar view, showing an additional pipe. Fig. 4 is a broken vertical section, showing an additional pipe for cleaning the interior of the pump barrel.

45 50 Similar characters of reference are used to indicate the same parts throughout the several views.

A casing 1 of ordinary construction is shown with an open lower end and perforations 2 extending some distance from the lower end. A pump line pipe 3 is centrally

positioned in the casing 1 and extended down within casing 1. The pipe 3 is adapted to be moved vertically within casing 1, the object being to let the pipe 3 down gradually when there is something to be broken up to be cleaned out of the well. Pipe 3 is used both as a pump line and as a cleaning pipe for forcing a fluid down to clean out mud and sand. The upper end of pipe 1 is opened for the outward passage of material to be removed from the well. The pipe 5 is used in combination with the pipe 3. Air, water, or steam is forced down the pipe 3 and this operation will force the sand, mud, and other material upwardly between the pipe 1 and the pipe 3. In order to aid the operation of the pipe 3, air is forced down the pipe 5 and allowed to escape out of the open end 6 of the pipe 5. The air escapes from the pipe 6 upwardly and thus tends to relieve the great weight of the material about the lower part of the pipe 1. The pressure will cause the air escaping from the end 6 to spread around the pipe 3 within the casing 1 and thus lift the column uniformly. When the pipe 3 is being let down gradually for the purpose of breaking up settled matter material within the casing 1 and perforations 2, air, water, or steam is forced down the pipe 3 and will break the substance to be removed, loosening the substance within casing 1 and the perforations 2 and loosening the material on the outside of casing 1 so that as the pipe 3 passes on down, the matter on the outside of casing 1 to be removed will pass through the perforations 2 above the end of pipe 3 and thus be carried on out of the casing 1 which is open at the upper end for the outward passage of all matter to be removed from within and without the casing 1.

55 In case of oil wells wherein paraffin or asphalt has become caked in and about the bottom of casing 1, hot steam is forced down the pipe 3 to cut away the paraffin, asphalt, or other substance so that such substances can be forced up the casing 1 and out of the well. The pipe 3 will be let down gradually to cut away the paraffin or other substances as the pipe descends. The steam pressure escaping from the bottom of the pipe 3 will loosen the paraffin and the paraffin will rise to the top of the water to be forced out of the well by water which will be forced down pipe 3. When all matter about the bottom of casing

- 1, within and without the pipe, has been broken and loosened up, water or other fluid pressure may be forced down pipe 3 to drive the matter out between the pipe 3 and pipe 5 1, and air may be used through pipe 5 to assist this operation. When the paraffin and other substances have all been cleaned out of the well, the strata from one well to another may be blown out with hot steam and air.
- 10 The upper end of pipe 1 may be sufficiently closed while the strata to adjacent wells are being loosened. A plug 4 may be used when the strata between different wells are to be blown. This plug 4 is perforated for the 15 passage of pipes 3, 5, and 7. The plug 4 may also be used to confine the heat of the steam within casing 1 while the paraffin or other substance is being loosened. Chemicals may be used with the steam for the purpose of breaking up the paraffin, or asphalt, or the chemicals may be used without the steam.

Should the pipe 3 become clogged in and about the bottom thereof, a pipe 7 may be 25 used to force steam or compressed air down about the pump barrel or lower part of pipe 3. When the pump barrel is being used in connection with the working barrel 3, an additional small pipe 7 may be let 30 down in the line casing 1 between the barrel of pipe 3 and the pipe 1. As this pipe 7 is let down within pipe 1 and outside of pipe 3 hot steam is run down the pipe 7 to heat the pipe 3 and the pump barrel which 35 is a continuation of the pipe 3. This will melt the paraffin inside of pipe 3 and within the casing 1. While the pump barrel is at work in connection with pipe 3, the water and oil at the bottom of pipe 3 will be heated 40 and as the hot oil and water rises in pipe 3, this pipe 3 will be completely cleaned out. Thus the pipe 3 can be cleaned out without removing the pipe 3 from the casing 1. Hot steam is discharged from pipe 7 as this pipe 45 is gradually let down in pipe 1. This will heat pipe 3 and aid in loosening any paraffin or asphalt that may be clinging to the inside of pipe 3, and when the hot water and oil rise or are raised from the bottom of pipe 50 3 up through this pipe 3, the paraffin or asphalt will be carried on out of the well.

Provision is also made for introducing hot steam or other cleansing element down with-

in the pipe 3 and the lower end thereof which constitutes the pump barrel. A pipe 55 8 is run down within the pipe 3 when this pipe is being used as a pump line, the pipe 8 being let down by the side of the pump rod 9. Hot steam or other cleansing fluid is 60 forced down the pipe 8 to remove any paraffin or other matter that may be accumulated about the pump rod and valves and on the inside of pipe 3. The pipe 8 may be fitted with a smooth taper nozzle 10 to prevent the injury of the pump rod or valve 65 while being placed in or removed from the pipe 3 and also to give greater force to the steam that is put into pipe 3. When the pipe 3 is used for cleaning purposes during the clearing of the casing 1 the pump rod 9 70 and the valves may be removed from the pipe 3.

In case there should be abnormal heat in the oil well sufficient to cause a crystallization of hydrocarbon elements into carbon, 75 it is apparent that cold air can be forced down in the well to regulate the heat and any of the pipes above described can be used for this purpose.

What I claim, is,—

1. In an apparatus for cleaning wells, the combination with a line casing having perforations in the side near the bottom end thereof, of an interior pipe centrally positioned in said casing and vertically movable 85 therein for forcing hot cleaning fluids downwardly and out through said perforations, and a pipe extending down between the walls of said pipes and having the end bent and extended upwardly for supplying a lift- 90 element under a column of fluid to be drawn out of the well.

2. In an apparatus for cleaning wells, the combination with a line casing having perforations in the side thereof near the lower 95 end, of a combined cleaning pipe and working barrel extending centrally down in said casing and vertically movable therein, means for forcing hot fluids down without said pipe and within said casing, and means for forcing air down under the liquids to be drawn out of the well.

In testimony whereof, I set my hand this 1st day of January, 1916.

GEORGE W. DEATS.
